UNITED STATES PATENT OFFICE

169,806

BRACELET DISPLAY STAND

Armand J. Garreau, Newport, R. I.

Application June 14, 1951, Serial No. 15,537

Term of patent 14 years

(CL. D80—9)

To all whom it may concern:

Be it known that I, Armand J. Garreau, a citizen of the United States, residing at Newport, State of Rhode Island, have invented a new, original, and ornamental Design for a Bracelet Display Stand, of which the following is a specification, reference being had to the accompanying drawing, forming a part hereof.

In the drawings,

Fig. 1 is a front view of a bracelet display stand showing my new design;

Fig. 2 is a side view thereof; and

Fig. 3 is an end view thereof.

I claim:

The ornamental design for a bracelet display stand, as shown.

ARMAND J. GARREAU.
